UNITED STATES PATENT OFFICE.

FRANCIS H. BROWN, OF GLENOLDEN, PENNSYLVANIA.

PRESSURE-RESPONSIVE DEVICE.

Application filed March 25, 1920, Serial No. 368,665. Renewed May 10, 1923.

To all whom it may concern:

Be it known that I, FRANCIS H. BROWN, a citizen of the United States, residing at Glenolden, in the county of Delaware and State of Pennsylvania, have invented an Improvement in Pressure-Responsive Devices, of which the following description, in connection with the accompanying drawings, is a specification, like characters on the drawings representing like parts.

The invention to be hereinafter described relates to differential pressure responsive devices, and more particularly to devices responsive to variations in static and kinetic fluid pressures. The device may be employed for indicating, registering, measuring, regulating, and other purposes.

Heretofore, devices have been employed for transmitting differential static and kinetic fluid pressures. For example, in steam generators the steam supply main leading therefrom has been provided with an orifice plate, and a pipe has been led from the main at one side of the plate to transmit static pressure of the steam to a regulating instrumentality, and a pipe has been led from the main at the opposite side of the orifice plate to transmit kinetic steam pressure to the regulating device.

The steam main may be constructed of sections having adjacent flanges, and the orifice plate may be introduced between and secured to said flanges. It is also necessary to specially construct the steam main sections so as to connect the static steam pressure pipe and the kinetic steam pressure pipe thereto. To connect said pipes as described, is an inconvenient operation, and in practice it is found that in many instances it is difficult to obtain the static and kinetic steam pressure variations thereby.

One of the purposes of the present invention, therefore, is to provide a simple and efficient device which may be quickly and readily introduced into the steam main, and whereby the static and kinetic steam or other fluid pressure variations may be efficiently received and transmitted to any instrumentality to be operated or affected thereby.

Also, in some cases it is desirable that the steam shall flow through the main in one

direction, and in other cases in the opposite direction. Heretofore, with the orifice plate and pressure transmission pipes connected to the main as described, the construction has been adapted to the flow of the steam through the main in one direction only, and if it is desired to have the steam flow in the opposite direction, it has been necessary to disconnect the pipes, exchange the positions thereof, and reconnect the same to the main.

Another purpose of the invention, therefore, is to provide a device which is adapted to transmit static and kinetic fluid pressure variations when the fluid is flowing through the main in either direction.

With the aforesaid and other purposes in view, the character of the invention may be best understood by reference to the following description of one good form thereof shown in the accompanying drawing, wherein:

Fig. 1 is a sectional view through a device embodying the invention and shown secured to a main; and

Fig. 2 is a vertical section taken on the line 2—2 of Fig. 1.

The device embodying the invention may be applied to a pipe or conduit through which steam or other fluid pressure may flow. In the present instance, a steam supply main 1 is shown, which may lead from a steam generator of usual construction, and therefore, unnecessary to show herein. This main may be formed in standard sections 3 and 5 having flanges 7 and 9.

The static and kinetic steam pressure responsive device may be conveniently introduced between the flanges of said pipe sections. One good form of the device comprises a plate 11 which may have an external diameter corresponding to the diameter of the flanges 7 and 9. This plate may be secured between said flanges by any suitable means, in the present instance, in the form of bolts 13 extending through said plate and flanges. The plate may be provided with a central orifice 15 substantially smaller than the internal diameter of the steam main.

One reason why the kinetic steam pressure

transmission pipe has not satisfactorily received and transmitted variations in the kinetic steam pressure, is due to the fact that this pipe has been connected to the steam main at one point, and at a substantial distance from the orifice of the plate. The present invention contemplates that the kinetic steam pressure which is a negative pressure, may be taken and transmitted from the entire periphery of an orifice or passage surrounding the orifice. In the present instance, this passage is in the form of a groove 17 which may be formed in the orifice plate to afford a protected space or cavity and communicate with the orifice throughout the perimeter thereof. The edges 19 of the orifice preferably are beveled so as to present sharp lines of juncture with said groove, thereby contributing to efficient transmission of the kinetic steam pressure variations to the groove 17. The orifice may be of any desired shape or contour, but for purposes of illustration, in the present instance, it is shown as circular. Communicating with the groove 17 is a port 21 conveniently extending radially from said groove toward the periphery of the plate. The outer end portion of this port may be counterbored and tapped to receive a pipe 23 for transmitting the kinetic pressure to the instrumentality desired.

As stated, one of the purposes of the invention is to provide a device which may be employed when the steam or fluid is flowing through the main in either direction. To accomplish this, in the present instance, the orifice plate may be provided with a port 25 having a mouth 27 at one side of the orifice plate, and a port 29 may be provided having a mouth 31 at the opposite side of said plate. The outer end portions of these ports may be counterbored and tapped to receive pipes 33 and 35 communicating with a horizontal pipe 37, communicating in turn with a vertical pipe 38 for transmitting the static steam pressure to the point desired. The pipe 33 may have a valve 39, the pipe 35 may have a valve 41, and the pipe 37 may have valves 43 and 45 at opposite sides of the pipes 33 and 35. The construction is such that when the steam is flowing through the main in the direction indicated by the arrow 47, the valve 39 may be closed, and the valve 41 may be opened, so that the port 29 will transmit the static pressure of the steam from the main at the right of the orifice plate to the pipe 35 and thence to the pipes 37 and 38. The direction of the transmission of the static steam pressure through the pipe 37 will depend upon whether the valve 43 or the valve 45 is opened.

If the steam is flowing through the main in the direction indicated by the arrow 49, the valve 41 will be closed, and the valve 39 will be opened, thereby admitting the static

steam pressure at the left of the orifice plate through the port 25 and the pipe 33 to the pipe 37. The direction of transmission of the static steam pressure through the latter pipe will depend upon whether the valve 70 43 or the valve 45 is opened.

The construction is such that the static and kinetic steam pressure variations will be efficiently transmitted from the orifice plate to the instrumentality to be controlled thereby. The kinetic steam pressure is most pronounced directly through the contracted opening afforded by the orifice plate, and since the circumferential groove 17 and port 21 communicate directly with this orifice, 80 the variations in the kinetic steam pressure will be definitely received and transmitted therethrough to the instrumentality to be operated in response to such variations. The mouths of the ports for transmitting static steam pressure variations may be located in the orifice plate a substantial distance within the main, and since they face the direction in which the steam is flowing, they will efficiently serve to receive and transmit the 85 variations in the static steam pressure, and the ports 25 and 29 communicating with the pipe 37 through the branch pipes 33 and 35 will definitely alternatively transmit the 90 variations in the static steam pressure to the 95 instrumentality to be controlled thereby.

It will be understood that the invention is not limited to the specific embodiment shown, and that various deviations may be made therefrom without departing from the 100 spirit and scope of the appended claims.

What is claimed is:—

1. A device of the character described, comprising a plate having an orifice therein, a circumferential groove in said plate communicating with said orifice, a port extending through said plate from the periphery thereof to said groove, a port extending from the periphery of said plate having a mouth opening at one face of said plate, and a port 105 extending from the periphery of said plate having a mouth opening at the opposite face of said plate.

2. The combination with a fluid supply pipe, of a plate therein having an orifice, and a circumferential groove opening into said orifice, a port communicating with said groove adapted to lead to a pipe to transmit kinetic fluid pressure from said fluid supply pipe, and a pair of ports having mouths 115 opening at opposite faces of said plate for alternatively transmitting static fluid pressure from said fluid supply pipe according to the direction of flow of fluid in the latter.

3. A device for transmitting static and kinetic fluid pressures, comprising means having an orifice therein, a continuous groove communicating with said orifice throughout the perimeter of the orifice, a port communicating with said groove for transmit- 125 130

ting kinetic fluid pressure, and a port opening at one side of said means for transmitting static fluid pressure.

4. A device of the character described, comprising a plate adapted for insertion between two pipe sections and having an orifice therein, a groove communicating with the orifice throughout the perimeter thereof, a port extending from the groove to the outer edge of the plate for transmitting kinetic fluid pressure, and a port opening at a face of the plate and extending to the outer edge of the plate for transmitting static fluid pressure directly from one of the pipe sections through the plate.

5. A device of the character described, comprising a plate having an orifice therein, a groove surrounding the orifice and communicating with the latter throughout the perimeter thereof, the edges of the orifice at opposite sides of said groove being beveled, a port in said plate for transmitting kinetic fluid pressure from the orifice and groove, and a port in said plate opening at a face of said plate for transmitting static fluid pressure from one side of said plate.

6. A device for transmitting static and kinetic fluid pressures, comprising means having an orifice therein, a groove communicating with the orifice throughout the perimeter thereof, a port communicating with said groove for transmitting kinetic fluid pressure therefrom, and ports in said plate opening at opposite faces of said plate to transmit static fluid pressure therefrom according to the direction of flow of the fluid through the orifice.

7. A device for transmitting static and kinetic fluid pressure, comprising integral means having an orifice therein and a continuous groove in said means communicating with said orifice throughout the perimeter of the latter, said means having a port communicating with said groove for transmitting kinetic fluid pressure, and a port in said member opening at a face thereof for transmitting static fluid pressure.

8. A device for transmitting static and kinetic fluid pressure, comprising means adapted for introduction into piping and having an orifice therein, a port in said means communicating with said orifice for transmitting kinetic fluid pressure, said means having provision for transmitting static fluid pressure through said means from either side thereof according to the direction of flow of fluid through the orifice.

9. A device for transmitting static and kinetic fluid pressure comprising a member adapted for introduction into piping and having an orifice therein, a port in said member communicating with said orifice for transmitting kinetic fluid pressure, and a pair of independent ports in said member and opening at opposite sides of said mem-

ber for transmitting static fluid pressure according to the direction of flow of fluid through the orifice.

10. A device of the character described comprising an orifice unit having a groove constituting a protected cavity surrounding the orifice in said unit for establishing a standard of pressure, and ports through the unit providing differential pressures.

11. A device of the character described comprising an orifice unit having an intermediate groove constituting a protected cavity surrounding the orifice in said unit for establishing a low pressure at the point of highest velocity, and ports through the unit providing differential pressures.

12. A device of the character described comprising an orifice unit having a groove intermediate its exposed faces affording a protected cavity surrounding the orifice in said unit for establishing kinetic pressure at the point of highest velocity, and ports through the unit providing differential pressures.

13. A device of the character described comprising an orifice unit having a substantially enclosed groove affording a protected cavity surrounding the orifice in said unit for establishing and transmitting kinetic pressure at the point of highest velocity, and subsidiary ports through the unit for diverting differential pressures.

14. A device of the character described comprising an orifice unit having a groove affording a concentric protected cavity around the orifice in said unit for establishing and transmitting kinetic pressure at the point of highest velocity, and subsidiary ports through the unit for diverting static pressure.

15. A device of the character described comprising an orifice unit having a groove affording a concentric protected cavity around the orifice in said unit for establishing and transmitting kinetic pressure at the point of highest velocity, said orifice having its edges flared to provide a sharp line of juncture with the cavity, and subsidiary ports through the unit for diverting static pressure.

16. A device of the character described comprising a differential pressure unit having an orifice embodied therein for establishing a varying working standard of pressure which is correlated to and varies coincidentally with other but different varying pressures associated with said unit, a groove-like cavity in said unit forming a protected pressure transmitting port openly communicating with and completely surrounding the aforesaid orifice at the point of highest velocity, and means for establishing, diverting and transmitting static pressure.

17. A device of the character described comprising a differential pressure unit hav-
